TYPOGRAPH-GESELLSCHAFT M. B. H., OF BERLIN, GERMANY

MATRIX-SETTING AND TYPE-LINE-CASTING MACHINE

Application filed November 21, 1928, Serial No. 408,892, and in Germany April 29, 1929.

This invention relates to a matrix setting and type-line casting machine with matrices guided in a cycle on wires, in which the line set after casting is brought by a vertically adjustable carriage to the distributing wires and deposited on the same by a slide. Hitherto the above mentioned carriage was moved by means of a simple rack and pinion gear which received its drive from the main shaft 5 of the machine, which shaft also operated the slide by means of a further drive. This arrangement does not insure an accurate working of the two drives, more particularly when the machine parts are worn, as the slide 10 must not move until the carriage is exactly in its uppermost position, and the latter must not descend until the slide has returned to its initial position.

According to this invention, the operation 20 of the slide is effected by the rack and pinion gear moving the carriage, and the said gear is made for this purpose in two parts. During the raising of the carriage, both parts of the rack and pinion gear are coupled together, and are uncoupled only on the highest position being reached, so that one part continues to work and moves the slide, whereupon both parts of the rack and pinion gear are again coupled together.

30 A construction according to the invention is illustrated by way of example in the accompanying drawing in which:

Figure 1 is a side elevation of the machine looking on the casting point, the casting pot 35 being omitted,

Figure 2 shows on an enlarged scale the bottom part of the carriage drive,

Figure 3 is a side elevation of Figure 2,

Figure 4 shows the upper part of the carriage drive,

Figure 5 is a section on line V—V of Figure 4,

Figure 6 is a section on line VI—VI of Figure 2,

45 Figures 7—9 show part of Figure 2 on an enlarged scale, in three different positions,

Figure 10 is a detail view of a locking device for the carriage,

Figure 11 is an elevation of the matrix 50 slide,

Figure 12 a section on line XII—XII of Figure 2 and

Figure 13 a section on line XIII—XIII of Figure 1.

The matrices 42 set to a line and suspended on wires 1, are pushed in the well-known manner in the direction of the arrow *a* on to the wires 2 of a carriage 3, cast there and then raised by the carriage 3 in the direction of the arrow *b* until, in the highest position 65 of the carriage, they are pushed by a slide 4 to the distributing wires 5 in order to pass then in the direction of the arrow *c* into the case (not shown).

The invention relates to the driving of the carriage 3 and of the slide 4. To this end, a shaft 6 continuously driven by a belt pulley 74, drives by means of a gear (not shown) a disc 7 (Figure 3) with a stop 8 which acts on a double lever 10 rotatable about 9. The bottom end of this lever is situated under a slide 12 (see also Figure 2) guided on the machine bed 11 by means of slots and screws, and situated under a stop 13. The latter is rigidly secured to a toothed rack 16 guided 70 in the machine bed 11 by means of an arm 14 and of a roller 15. To the upper end of this rack is normally coupled a second rack 17 which has a spring-controlled pin 18 that engages with a rod 19 guided in the machine bed 11. The bottom end of this rod rests laterally against a lever 21 rotatably mounted about 20 (Figure 12) and controlled by the pressure of a spring 22, the said lever carrying one half of a coupling 23. As soon as the 75 double lever 10 is rotated by the disc 7, the racks 16, 17 and therefore the rod 19 will be slightly raised by means of the parts 12, 13, and the rod 19 will release the lever 21 so that the coupling 23 will be thrown in. 80

On the rod 19 are mounted two pins 77, 78 (Figure 2), the bottom one of which, in the position of the rod 19 locking the coupling 23, rests on the machine bed 11, whilst the upper one 77 strikes against the machine bed after the raising of the rod 19, so that the rod 19 cannot continue to rise, but forces back the spring controlled pin 18, is thus released from the rack 17 and descends with the bottom end on the thrown-in coupling lever 21. 85

Owing to the throwing-in of the coupling, a toothed wheel 24 (Figure 3) will be rotated which through intermediate wheels 25, 26, rotates a pinion 27 engaging with the rack 16, so that the rack will now be raised further by the machine. In this way will also be raised the rack 17 with which meshes a pinion 28 (Figure 2) on the spindle of which is mounted a second larger toothed wheel 29. 10 The latter meshes with a rack 30 which constitutes a weight which is connected (see Figures 1 and 4) by a chain 31 passing over rollers, to the carriage 3. The raising of the rack 17 will therefore lower the weight 30 and thereby the carriage will be raised until it reaches the highest position, shown in dotted lines in Figure 4.

The carriage 3 is constituted by a frame which is built up of four girder-like frame members 32, 33 (see Figure 13) arranged at a distance apart, between which are secured in two rows the guide wires 2 and which carries laterally rollers 35. The latter slide on girder-like members 36, 37, which constitute the guide frame for the carriage. On the upper transverse part of the carriage 3 is mounted a pin 38 and on the upper transverse part of the frame 36, 37 is rotatably mounted at 39, a spring controlled catch 40 with a stop 41. When the carriage has assumed its highest position, the catch 40 engages the pin 38, owing to which the carriage is locked in that position.

It is necessary to prevent any further movement of the gears 27, 28, 29, 30 when the carriage is in the highest position and the matrices 42 must be pushed from the wires 2 on to the wires 5 by the slide 4, for which purpose the following arrangement is used:

40 As already stated, the racks 17, 16 are not rigidly connected together, but the rack 17 is provided at the bottom with a round rod 43 (see Figure 6) on which the rack 16 is guided by a suitable bore. On a bar 79 connected to the rack 16 is mounted rotatably about 44 (see Figures 2, 3 and 7-9) a catch 45 which engages by means of a projection 46 with a pin 47 provided on the rack 17, and carries an oblique arm 48. When the rack 16 is raised, the rack 17 will be raised at the same time by the catch 45 and pin 47 until the oblique arm 48 strikes a cam face 49 provided on the machine bed. In this way the catch 45 will be released, so that it assumes the position shown in Figure 9. Owing to this, the rack 17 will no longer be raised, nor will any further raising of the carriage 3 take place, but the rack 17 will also be unable to sink as owing to the locking device 38, 40 the carriage and therefore the parts positively connected to it, will be locked.

The rack 16 will however continue to move in order to remove the matrices 42 from the carriage 3 by means of the slide 4. To this end, on the rack 16 is provided a fixed stop 50

which, on the rack being raised, strikes a rod 51 which, by means of levers 52, 53, turns a lever 54 about a pin 75 which is connected by a hinged rod 55 to a pin 56 (see Figures 4 and 5) on which is mounted a rectilinearly guided rod 57 carrying the matrix slide 4. The matrix slide is constituted by a vertical rod (Figure 11) with lateral projections 58 which engage between the wires 2 of the carriage 3 and thereby push in front of them the matrices suspended to the said wires. On the pin 56 is mounted a roller 59 which travels on a horizontal rail 60. Consequently, by raising the rod 51 owing to which the parts 52-59 are brought into the intermediate position indicated in chain-dotted lines in Figure 4, the slide 4 will be horizontally advanced. In the position of rest, the slide is situated between the members 36, 37 of the frame for the carriage 3 (Figure 5).

To the upper end of the frame 36 is secured a block 61 in which is adjustable a spring-controlled pin 62 (see Figure 10). The latter has a flange 63 against which rests the slide 4. In the non-operative position of the said slide, the spring-controlled pin is forced back as indicated by the dotted lines in Figure 10. When however the carriage 3 has been brought to its uppermost position, and the slide 4 is advanced, the spring-controlled pin 62 will be released and will spring into a hole 64 of the carriage 3, owing to which the latter will be locked until the slide 4 returns to its non-operative position and thereby forces back the spring-controlled pin.

During its advance, the slide 4 releases the locking device 36, 40. To this end, on the rod 55 is provided an arm 65 which presses against the projection 41 of the catch 40, so that the latter releases the pin 38.

As soon as the rack 16 has reached its highest position, a stop 66 (Figures 2 and 3) provided on its lower end, strikes a pin 67 which is guided in the arm 14, and this pin presses against a bell crank lever 68 so that the latter is turned. The end of this bell crank lever presses against the free end of the lever 21 (Figure 12) owing to which the latter is turned, and the coupling 21 thrown out. The power drive is therefore stopped.

The working of the machine is as follows:—

As soon as the line is cast, the shaft 6 raises by means of the parts 7-13 the rack 16 and the rack 17 connected to the latter, and therefore the rod 19 owing to which the coupling 23 is thrown-in. Consequently, the gears 23-27 continue to raise the racks 16, 17 until the carriage 3 reaches its highest position and is locked by the locking device 38, 40. At this moment, the catch 45 is released by the stop 49, so that the rack 17 stops, whilst the rack 16 is raised still further, being guided on the round rod 43, and drives by means of the stop 50 the rod 51, owing to which the

slide 4 is moved forward by the rods 52-57. During this movement first the spring-controlled pin 62 is released and locks the carriage 3, whereupon the spring controlled catch 38, 40 is released. A spring-controlled pin 84 provided on the carriage 3 (Figure 4), springs into a corresponding hole of the catch 40 and locks it, so that it can no longer become coupled to the pin 38.

When the rack 16 has reached its highest position and the slide 4 assumed its outermost operative position, the stop 66 will turn by means of the pin 67 the bell crank lever 68 and throw out the coupling 23, the rod 19 dropping in front of the coupling lever 21 and locking it (Figure 12). A spring 76 mounted on the rod 51 and cocked during the raising of the rod, presses down against the rod 51, owing to which the slide 4 is moved into its extreme right hand position, so that the locking device 62, 64 of the carriage 3 is released. At the same time, the descending rod 51 which presses against the stop 50, moves the rack 16 downwards, until it is coupled again to the rack 17 owing to the springing-in of the catch 45. Only after the locking device 62, 64 has released the carriage 3, that is to say the slide 4 has assumed its position of rest, the carriage 3 will be able to descend as its weight is greater than that of the rack 30. During this movement, its spring-controlled pin 84 will be released from the catch 40 which will then return to its vertical position ready for locking, and the two racks 16, 17 will be lowered by the gears 30, 29, 28. In the lower position of the rack 17, the spring-controlled pin 18 will again spring into the rod 19 (Figure 9).

If a repeated casting of the same line is to be effected, the carriage 3 is locked in its lowest position (Figure 13) by means of a hand-operated bolt 69, which engages in a hole 70 of the carriage, and in this way the rack 17 will also be locked. In this way, the locking rod 19 will also stop, and no throwing-in of the coupling 23 can take place. The rack 16 however moves upwardly and must be able to move relatively to the catch 45. To this end, on the rack 16 is provided a bar 79 which is secured by means of screws engaging with elongated holes 80. This bar carries in an arm 81 a pin 83 controlled by the action of a spring 82, which pin is moreover supported in the stop 13. During the ordinary working, the parts 16, 79 move as a unit. If however the rack 17 is locked, there will be produced, during the raising of the rack 16 by the parts 47, 46, 45, 79, 81, a pressure which will compress the spring 82, and as only the rack 16 rises, the stop 71 (Figure 8) secured to it, will be pressed against a pin 72 of the catch 45, owing to which the latter will release the rack 17, so that both racks will now be able to move into each other, without the coupling 23 being thrown in. This effect is

produced also when for other reasons, for instance by lead sprayer, the carriage is held in its lowest position.

If in the uppermost position of the carriage, the matrices should get out of order or if there should be any other trouble, so that the movement of the slide 4 is stopped, the lever system 52, 53 must nevertheless be able to move. To this end, the lever 53 is formed as a double lever, and its free end is connected by a spring 73 (Figure 4) to the lever 54. Owing to this, the lever 53 can oscillate relatively to the lever 54 without driving the latter. This spring connection avoids at the same time any risk of injury to the matrices, which is liable to be caused by prematurely pulling down the carriage 3.

I claim:—

1. In a matrix setting and line casting machine, matrices guided on wires in a cycle, a carriage for raising the line set after the casting to distributor wires, pushing means for pushing the line set on to the distributor wires and members for lifting said carriage and operating said pushing means and adapted to be automatically interconnected so as to operate as a single body and to be again separated so as to act independently of each other at predestined stages of operation.

2. In a matrix setting and line casting machine, matrices guided on wires in a cycle, a carriage for raising the line set after the casting to distributor wires, pushing means for pushing the line set on to the distributor wires, longitudinally adjustable members for lifting said carriage and operating said pushing means and adapted to be automatically interconnected so as to operate as a single body and to be again separated so as to act independently of each other at predestined stages of operation, other means for locking said carriage in its uppermost position and still other means for releasing said carriage after the line set has been delivered to the distributor wires.

3. In a matrix setting and line casting machine, matrices guided on wires in a cycle, a carriage for raising the line set after the casting to distributor wires, a slide for pushing the line set on to the distributor wires, two toothed racks for lifting said carriage and operating said slide and adapted to be coupled together so as to operate as a single rack and to be again separated, so as to act independently of each other at predestined stages of operation, means for initially lifting said racks and thereby throwing in a coupling and a rack and pinion gear for further raising said racks.

4. In a matrix setting and line casting machine, matrices guided on wires in a cycle, a carriage for raising the line set after the casting to distributor wires, a slide for pushing the line set on to the distributor wires, two toothed racks being longitudinally ad-

justable to each other in a straight line and serving for lifting said carriage and operating said slide, a catch rotatably mounted on the bottom rack and when the racks are coupled together engaging a stop of the upper rack, and a fixed stop for releasing said catch in the highest position of the carriage.

5. In a matrix setting and line casting machine, matrices guided on wires in a cycle, a carriage for raising the line set after the casting to distributor wires, a slide for pushing the line set on to the distributor wires, two longitudinally adjustable toothed racks for lifting said carriage and operating said slide and adapted to be coupled together so as to operate as a single rack and to be again separated, so as to act independently of each other at predetermined stages of operation, a continuously rotating shaft, a double lever turned by said shaft and slightly raising the racks coupled together, a coupling thrown in by this movement of said lever and a rack and pinion gear for further raising said racks.

23 6. In a matrix setting and line casting machine, matrices guided on wires in a cycle, a carriage for raising the line set after the casting to distributor wires, a slide for pushing the line set on to the distributor wires, two longitudinally adjustable toothed racks for lifting said carriage and operating said slide and adapted to be coupled together so as to operate as a single rack and to be again separated, so as to act independently of each other at predetermined stages of operation, a continuously rotating shaft, a double lever turned by said shaft and slightly raising the racks coupled together, a coupling thrown in by this movement of said lever, a rack and pinion gear for further raising said racks and a rod being mounted in an easily detachable manner on the upper rack, which rod holds the coupling in the disengaged position, is driven during the raising of the rack and thus releases the coupling, but is thereupon uncoupled from the rack and is always ready for locking.

7. In a matrix setting and line casting machine, matrices guided on wires in a cycle, a carriage for raising the line set after the casting to distributor wires, a slide for pushing the line set on to the distributor wires, two longitudinally adjustable toothed racks for lifting said carriage and operating said slide and adapted to be coupled together so as to operate as a single rack and to be again separated, so as to act independently of each other at predetermined stages of operation, a continuously rotating shaft, a double lever turned by said shaft and slightly raising the racks coupled together, a coupling thrown in by this movement of said lever and a rack and pinion gear for further raising said racks the bottom rack being posi-

tively connected to the machine shaft by a gear, and the upper rack similarly connected by a second gear to a third rack formed into a weight and in its turn connected to the carriage by a tension member passing over rollers.

8. In a matrix setting and line casting machine, matrices guided on wires in a cycle, a carriage for raising the line set after the casting to distributor wires, a slide for pushing the line set on to the distributor wires, two longitudinally adjustable toothed racks for lifting said carriage and operating said slide and adapted to be coupled together so as to operate as a single rack and to be again separated so as to act independently of each other at predetermined stages of operation, a continuously rotating shaft, a double lever turned by said shaft and slightly raising the racks coupled together, a coupling thrown in by this movement of said lever and a rack and pinion gear for further raising said racks the horizontally guided slide being connected by a system of levers to a vertical rod which, after the uncoupling of the two racks, is raised by the rack continuing to move, and thereby moves the slide.

9. In a matrix setting and line casting machine, matrices guided on wires in a cycle, a carriage for raising the line set after the casting to distributor wires, a slide for pushing the line set on to the distributor wires, two longitudinally adjustable toothed racks for lifting said carriage and operating said slide and adapted to be coupled together so as to operate as a single rack and to be again separated, so as to act independently of each other at predetermined stages of operation, a continuously rotating shaft, a double lever turned by said shaft and slightly raising the racks coupled together, a coupling thrown in by this movement of said lever, a rack and pinion gear for further raising said racks the horizontally guided slide being connected by a system of levers to a vertical rod which, after the uncoupling of the two racks, is raised by the rack continuing to move, and thereby moves the slide and a spring cocked during the raising of the rod, moving back the slide after the pushing over of the matrices, and at the same time again lowering the rack by means of the rod.

10. In a matrix setting and line casting machine, matrices guided on wires in a cycle, a carriage for raising the line set after the casting to distributor wires, a slide for pushing the line set on to the distributor wires, two longitudinally adjustable toothed racks for lifting said carriage and operating said slide and adapted to be coupled together so as to operate as a single rack and to be again separated, so as to act independently of each other at predetermined stages of operation, a continuously rotating shaft, a double lever

turned by said shaft and slightly raising the racks coupled together, a coupling thrown in by this movement of said lever, a rack and pinion gear for further raising said racks a locking device locking the carriage in the highest position, which holds fast the said carriage and therefore the upper rack connected to it, after its uncoupling from the bottom rack.

10 11. In a matrix setting and line casting machine, matrices guided on wires in a cycle, a carriage for raising the line set after the casting to distributer wires, a slide for pushing the line set on to the distributer wires, two longitudinally adjustable toothed racks for lifting said carriage and operating said slide and adapted to be coupled together so as to operate as a single rack and to be again separated, so as to act independently of each other at predetermined stages of operation, a continuously rotating shaft, a double lever turned by said shaft and slightly raising the racks coupled together, a coupling thrown in by this movement of said lever and a rack and pinion gear for further raising said racks, the slide releasing at the beginning of its travel a second locking device for the carriage releasing during its further travel the first locking device and at the end of its return, again releasing also the second locking device so that only then the carriage can descend.

15 12. In a matrix setting and line casting machine, matrices guided on wires in a cycle, a carriage for raising the line set after the casting to distributer wires, a slide for pushing the line set on to the distributer wires, two longitudinally adjustable toothed racks for lifting said carriage and operating said slide and adapted to be coupled together so as to operate as a single rack and to be again separated, so as to act independently of each other at predetermined stages of operation, a continuously rotating shaft, a double lever turned by said shaft and slightly raising the racks coupled together, a coupling thrown in by this movement of said lever and a rack and pinion gear for further raising said racks the bottom rack and the catch carried by it, being adjustable relatively to each other to a limited extent, so that when the slide is locked in the lowermost position, the bottom rack can rise slightly relatively to the latch and release the latter by means of a stop provided on the same, for the purpose of preventing the coupling from being thrown in.

In testimony whereof I affix my signature.
JULIUS DORNETH.
